DESCRIPTION

FIG. 1 is a perspective view of a double aperture boxer brief harness showing my new design;

FIG. 2 is a view in front elevation thereof;

FIG. 3 is a view in rear elevation thereof;

FIG. 4 is a view in front elevation thereof in an inside-out configuration;

FIG. 5 is a view in rear elevation thereof in an inside-out configuration;

FIG. 6 is a partially exploded perspective view thereof; and, FIG. 7 is a view in front elevation thereof in an inside-out configuration with the rear flaps opened.

Broken lines in FIGS. 2 through 5, and FIG. 7, represent unclaimed environment only and form no part of the claimed design. The mesh pattern, in each instance covers the entire panel on which it has been illustrated partially.
